G. WHITMAN

Des. 168,980

BRASSIERE

Filed Oct. 9, 1952

FIG. 1.

FIG. 2.

INVENTOR

Gertrude Whitman

UNITED STATES PATENT OFFICE

168,980

BRASSIÈRE

Gertrude Whitman, Jamaica, N. Y.

Application October 9, 1952, Serial No. 21,765

Term of patent 14 years

(Cl. D20—4)

To all whom it may concern:

Be it known that I, Gertrude Whitman, a citizen of the United States, residing at Parkview Apartments, 165-20 Highland Avenue, Jamaica, Long Island, State of New York, have invented a new, original, and ornamental Design for a Brassière, of which the following is a specification, reference being had to the accompanying drawing, forming a part hereof.

Fig. 1 is a front perspective view of a brassière showing my new design; and

Fig. 2 is an enlarged fragmentary perspective view of the brassière shown in Fig. 1.

I claim:

The ornamental design for a brassière, as shown.

GERTRUDE WHITMAN.
